(57) **CLAIM**

The ornamental design for a golf ball picker, as shown and described.

DESCRIPTION

FIG. 1 is a perspective view of the golf ball picker;
FIG. 2 is a perspective view thereof, with the picker being retracted into the handle;

FIG. 3. is a top plan view of FIG. 1

FIG. 4. is a side view of FIG. 4, all other sides being identical;

FIG. 5. is a top plan view of FIG. 2; and,

FIG. 6. is a side view of FIG. 2, all other sides being identical.

The broken line showing is for illustrative purposes only and forms no part of the claimed design.
